INVENTOR

ber W. Byerly
ATTORNEY

UNITED STATES PATENT OFFICE.

HENRY E. VAN NESS, OF ELMIRA, NEW YORK.

YARN CLEANER.

Application filed March 29, 1922. Serial No. 547,596.

To all whom it may concern:

Be it known, that I, HENRY E. VAN NESS, a citizen of the United States, residing at Elmira, in the county of Chemung and State of New York, have invented certain new and useful Improvements in Yarn Cleaners, fully described and represented in the following specification and the accompanying drawings, forming a part of the same.

10 This invention relates to yarn cleaners for eliminating from yarn impurities such as parts of seeds, parts of stems, slubs, specks, grains of sand, and other particles before the yarn is made into cloth, and thus improving the quality of the cloth made from the yarn and avoiding the necessity for excessive bleaching of the cloth.

An object of the invention is to provide a device adapted thoroughly to clean a traveling yarn without retarding the travel of the yarn, so that danger of breaking of the yarn in the cleaner is eliminated.

A further object of the invention is to provide a yarn cleaner adapted to discharge the particles removed from the yarn, without the use of any mechanically-driven parts.

A still further object of the invention is to provide a yarn cleaner including a plurality of cleaning elements so arranged that the yarn cannot be passed through the cleaner without being brought into operative relation with all the elements, thus insuring a thorough cleaning of the yarn regardless of carelessness on the part of the operator.

35 Other objects and advantages of the invention are hereinafter pointed out in connection with a detailed description of a specific embodiment of the invention.

40 A yarn cleaner embodying the invention and adapted to accomplish the objects above outlined may include a frame provided with a plurality of resiliently supported elements which are set into vibration by the travel of the yarn, and which, when vibrating, serve to separate particles from the traveling yarn and to discharge the particles from the cleaner. The vibratory elements are most desirably arranged so that they all operate upon a yarn traveling in a straight line, and 45 the frame may be provided with a cover which insures bringing the yarn into operative relation with all the elements when the cleaner is threaded.

In order that the invention may clearly be

understood, I will describe in detail a yarn 55 cleaner embodying the invention which is illustrated in the accompanying drawings, in which:—

Fig. 1 is a top view of the cleaner;

Fig. 2 is a side view sectioned on the line 60 2—2 of Fig. 1;

Fig. 3 is an end elevation on a larger scale, sectioned on the line 3—3 of Fig. 1;

Fig. 4 is a fragmentary plan view on a still larger scale, sectioned on the line 4—4 65 of Fig. 2, and showing the operative portions of some of the vibratory cleaning and deflecting elements;

Fig. 5 is an enlarged fragmentary vertical section on the line 5—5 of Fig. 3 showing 70 the manner in which the vibratory elements are mounted in the frame;

Fig. 6 is an enlarged perspective view of one of the vibratory deflecting elements;

Fig. 7 is an enlarged perspective view of 75 one of the vibratory cleaning elements; and

Fig. 8 is a fragmentary perspective view of one of the vibratory cleaning elements looking toward the cleaning edge, on a still larger scale.

The cleaner shown in the drawings is 80 adapted to operate upon a traveling yarn which is being drawn from a bobbin or other supply into a winding or spooling or other machine. The cleaner may conveniently be 85 secured to a portion of the frame of any such machine, and for this purpose there may be secured to the frame 10 of the cleaner a stud 11 containing a hole and provided with a set screw 12. It will be understood, however, that the cleaner may be mounted in any desired manner and will operate upon any traveling yarn regardless of the nature of the machine into which the yarn is being drawn.

The frame 10 of the cleaner may be rectangular and the ends 13 and 14 of the frame may conveniently be made integral with one side 15 of the frame. For a reason herein-after explained, it is desirable to form the 100 other side 16 of the frame of a separate piece of metal and to attach it to the ends 13, 14 in such manner that the distance between it and the side 15 of the frame may be varied. In the form shown, the side 16 has a dovetail connection with the ends 13 and 14 and is secured thereto by means of screws 17 105 which have a threaded connection with the

ends of the frame and pass through transverse slots 18 in the side 16, so that by loosening the screws the side 16 may be moved slightly toward or away from the side 15 of the frame.

On the end 13 of the frame, which I term the front end because it is the end from which the traveling yarn enters the cleaner, is mounted a tension device 19 of usual construction. The ends 13 and 14 are provided at their middles with recesses 20, 21 which permit a yarn A, which is passed over the tension device, to be drawn longitudinally across the middle of the frame, as indicated by the dotted lines in Figs. 1 and 2.

At the top of each of the sides 15 and 16 of the frame are long recesses 23, 22 which provide space for the mountings of the vibratory elements which are hereinafter described.

The top of the frame 10 is closed by a cover consisting of two pieces 26, 27 whose inner edges are spaced to provide a slot 28 adapted to permit the yarn to be drawn into the position indicated by dotted lines in Figs. 1 and 2. The cover pieces 26 and 27 are secured to the frame by means of screws 25 entering the ends of the frame and projections 29, 30 on the sides 15, 16 of the frame between the recesses 23 and the recesses 22.

A skirt 32 extends downwardly from the frame to confine the particles and any matter removed from the yarn by the cleaner. The skirt 32 may conveniently be formed of a single piece of metal and secured to the ends 13, 14 and the side 15 of the frame by screws 33. The skirt 32 is not attached to the side 16 of the frame and the skirt is of sufficient width to allow for the adjustment of the side 16 which is provided by the slots 18.

The vibratory cleaning elements 50, 50' extend inwardly from the sides 15, 16 of the frame. Each cleaning element may conveniently be formed from a single piece of sheet metal as shown. The thickness of the sheet metal is somewhat exaggerated in the drawings for the sake of clearness.

Each vibratory cleaning element 50 comprises a cleaning blade 53 and a resilient support 52. The outer end portion 54 of the support 52 is set in a transverse slot 51 extending downwardly from the bottom of one of the recesses 23 in the side of the frame. The support 52 extends inwardly from the side 15 of the frame and it is inclined toward the back end 14 of the frame. The blade 53 extends inwardly from the inner end of the support 52 and is inclined toward the front end 13 of the frame. The inclinations of the support 52 and the blade 53 are such that the inner end of the blade 53 is substantially in line with the outer end portion 54 of the support 52.

The outer end portion 54 of the support

52 is held in its slot 51 by means of a washer 55 which is forced down by a screw 56 (see Fig. 5). The recesses 23 in the side 15 of the frame provide space for the washers and the heads of the screws 56 below the lower surface of the cover piece 26. The outer end portion 54 is off-set from the remainder of the support 52, so that the top of the element lies close to the lower surface of the cover piece 26. A slight clearance is, however, allowed between the cleaning elements and the cover so as to leave them free to vibrate.

In the end of the cleaning blade 53 of each element 50 is a semi-circular notch 57 extending parallel to the sides of the frame. For convenience in threading, the upper portion 58 of the end above the groove 57 is also made parallel to the sides of the frame and is rounded off at its upper corner 59. In the form illustrated the lower portion 60 of the end below the groove 57 is also made parallel to the sides of the frame. The surface of the notch 57 and the front surface 61 of the blade 53 intersect in an acute edge 62, which I term the cleaning edge.

The cleaning elements 50' which are mounted on the side 16 of the frame are similar in form to the cleaning elements 50, and in the drawings the parts of the elements 50' are designated by the same numerals as the corresponding parts of the elements 50, a prime being added to each numeral.

The cleaning elements 50, 50' are arranged in the frame in staggered relation as illustrated. The inner ends of the elements 50 lie in a common plane and the notches 57 are aligned. The inner ends of the elements 50' lie in a common plane and the notches 57' are aligned. When the cleaner is adjusted for cleaning yarns of diameters substantially equal to that of the notches 57, 57', the distance between the sides 15 and 16 of the frame 10 is adjusted so that the planes in which the inner ends of the cleaning elements 50 and 50' lie are coincident and the centers of the notches 57, 57' lie on a straight line, which is the line of travel of the yarn A through the cleaner.

The notches 57 and the cleaning edges 62 of the elements 50 surround one-half of the circumference of the yarn A, while the notches 57' and the cleaning edges 62' of the elements 50' surround the other half of the circumference of the yarn. Each cleaning element is free to vibrate through the bending of its resilient portion. When the elements are in vibration, the center point of the cleaning edge of each element moves in a plane including the line of travel of the yarn and in a curve tangential to the yarn. Consequently, the movement of each cleaning edge is substantially longitudinal of the yarn, although in the normal position of each element its cleaning edge is

slightly closer to the yarn than in the other positions which the element occupies during its vibration. Thus, in the form illustrated, the movement of each cleaning edge has, in addition to the relatively large component longitudinal of the yarn, the relatively small component transverse to the line of travel of the yarn.

I have found that the vibratory cleaning elements arranged in the manner described are effective to detach from the yarn, particles adhering to it, and that the front surfaces 61, 61' of blades 53 of the elements tend to deflect these particles away from the line of travel of the yarn. I have found also, however, that a certain amount of fibrous material is necessarily removed from the yarn with the particles and that this fibrous material has a tendency to become re-entwined in the yarn after the particle has been detached from the yarn unless some means are provided for moving it to some distance from the yarn. Various means may be used for this purpose in cooperation with the cleaning elements, such as have been described. Thus, for example, air suction may be used for this purpose.

Vibratory deflecting elements 70, 70' are, however, the most satisfactory and economical means which I have found for moving the particles and any adhering fibrous matter to a safe distance from the yarn. These deflecting elements constitute a part of my invention. Each deflecting element may conveniently be formed from a single piece of sheet metal as shown. The thickness of the sheet material is somewhat exaggerated in the drawings for the sake of clearness.

Each deflecting element 70 comprises a blade 73 in a resilient support 72. The outer end portion 74 of the resilient support 72 is set in a transverse slot 71 in the side 15 of the frame in the same manner that the supports of the cleaning element 50 are set in the slots 51. The resilient support 72 extends straight inward from the side 15 of the frame, while the blade 73 extends transversely to the line of travel of the yarn and is inclined rearwardly and downwardly. The blade 73 may be curved as shown, or to a greater or less degree, or may be flat. The blade 73 has an inner edge 75 which is transverse to the resilient support 72 and is inclined to the line of travel of the yarn by reason of the inclination of the blade. The outer end portion 74 of the support 72 is off-set downward from the remainder of the support, so that the top of the element lies close to the lower surface of the cover piece 26. A slight clearance is, however, allowed so as to leave the element free to vibrate. To facilitate threading, the upper corner of the inner edge 75 of the element is rounded off at 79.

The deflecting elements 70' are similar in

form to the elements 70, and in the drawings the parts of the elements 70' are designated by the same numerals as the corresponding parts of the elements 70, a prime being added to each numeral. 70

The deflecting elements 70, 70' are arranged in the frame in pairs, each of the elements 70' being directly opposite one of the elements 70. The inner edges 75, 75' of each pair of deflecting elements are spaced apart by a distance substantially equal to the diameter of the yarn A so that they lie adjacent to the yarn on opposite sides thereof. The inner edges 75, 75' may, in their normal position, be parallel, as shown, or may, in certain cases, recede from one another, below the line of travel of the yarn, to assist in the clearing of accumulated matter from the opening between them. Each deflecting element is free to vibrate through the bending of its resilient portion. When the elements are in vibration the points of their inner edges which are normally immediately adjacent to the yarn move in a plane including the line of travel of the yarn and in curves tangential to the yarn. Consequently the movement of each inner edge is substantially longitudinal of the yarn, although in the normal position of each pair of deflecting elements their cleaning edges 80 are slightly closer together than in the other positions which the elements occupy during their vibration. 85

In the vibration of the deflecting elements 70, 70' the blades 73, 73' of each pair of elements turn outwardly from each other through the bending of the resilient supports 72, 72' of the elements. This turning movement is horizontal. Since the blades 73, 73' are oblique, that is, not perpendicular, to the direction of the turning movement, the inner edges 75, 75' of each pair of the blades 73, 73' are separated from each other to a greater extent at their lower ends than at their upper ends when the 90 blades are turned outwardly from each other. 100

Behind each pair of deflecting elements is a pin 80 having one of its ends fixed in the side 15 of the frame. The upper surfaces 115 of these pins lie in a plane tangential to the notches 57, 57' at their lower corners, so that the pins aid in placing the yarn in operative relation to the cleaning edges 62, 62' when the cleaner is threaded, and serve to 120 prevent the yarn from dropping below the notches 57, 57' in case the yarn is slackened.

The use of the cleaner is as follows:—

The cleaner is first adjusted in accordance with the diameter of the yarn in connection with which it is to be used. The adjustment is effected by loosening the screws 17 and moving the side 16 of the frame slightly inwardly or outwardly. If the diameter of the yarn is substantially 130

equal to that of the notches 57, 57', the side 16 is positioned as shown in the drawing so as to bring the centers of the notches 57' on a line with the centers of the notches

5 57. Owing to the compressibility of the yarn, yarns whose diameters vary somewhat from that of the notches 57, 57' may be successfully cleaned in the device adjusted as illustrated. If, however, the diameter 10 of the yarn is materially different from that of the notches, the cleaner should be adjusted so that the cleaning edges 62, 62' surround the yarn as closely as possible. This is done by moving the side 16 of the 15 frame slightly inwardly if a smaller yarn is to be cleaned, or slightly outwardly if a larger yarn is to be cleaned.

The cleaner is threaded by drawing the 20 yarn through the tension device 19, extending it across the top of the cleaner and then drawing it down into the slot 28 between the two cover pieces 26, 27. As the 25 yarn is drawn down it is guided to the center of the frame by the rounded corners 59 of the cleaning elements and the rounded corners 79 of the deflecting elements. The 30 yarn is pulled forward while it is drawn downwardly, and the forward movement of the 35 warn pulls each of the vibratory cleaning elements backward, thus causing the upper portions 58, 58' of the ends of these elements to move outwardly from their normal position, permitting the yarn to be drawn by them and into the notches 57, 57'. The pins 80 prevent it from being drawn 40 below the notches. The yarn then extends through the cleaner in a straight line and may be drawn forward by a winding or other machine not shown in the drawings.

45 In the operation of the cleaner, the vibratory cleaning and deflecting elements are set into vibration by the passage of the yarn across their edges and more particularly by the impingement against their edges of particles projecting from the yarn. As the 50 cleaning elements 50, 50' vibrate, the cleaning edges 62, 62' of these elements strike particles projecting from the yarn and brush them from the yarn. If a particle 55 is firmly entwined in the yarn it is usually not removed from the yarn by the first cleaning element which strikes it, but is merely loosened so that it may be detached by a subsequent cleaning element. The 60 particles which have been detached from the yarn and any fibrous matter which may adhere to them tend to be drawn along in the direction of travel of the yarn by the suction produced by the movement of the 65 yarn. These particles and this fibrous matter strike the deflecting elements 70, 70' and are directed downwardly inside the skirt 32, so that they do not become again entwined in the yarn. The portions of the 70 inner edges of the deflecting elements which

are adjacent to the yarn serve also to detach from the yarn some particles which have been merely loosened by the cleaning elements.

The vibration of the cleaning elements 75 and deflecting elements prevents the collection upon them of particles and any fibrous matter which is removed from the yarn. The particles and fibrous matter do not adhere to the pins 80 because the deflecting 80 elements positioned in front of each of the pins protect the pins. As a result all the particles and any fibrous matter removed from the yarn is directed downwardly within the skirt 32 and may be collected in any 85 desired manner at the bottom of the skirt.

I wish it clearly understood that my invention is by no means limited to the particular form and arrangement of parts which I have described. Furthermore, 90 many of the parts and features of the embodiment of the invention which I have illustrated and described may, under certain circumstances, be advantageously used independently of other parts and features with 95 which they are combined in said embodiment.

What is claimed is:

1. In a cleaner for removing particles from a traveling yarn, a blade having a portion of its edge adjacent to the yarn and resiliently held to permit free vibration of said portion of its edge, so that the blade is set into vibration by the impingement of particles projecting from the yarn and brushes 100 particles from the yarn by its vibration.

2. In a yarn cleaner for removing particles from a traveling yarn, a blade containing a notch partly encircling the yarn and having a front surface extending from said notch at an obtuse angle to the yarn and forming an acute edge at its intersection with said notch.

3. In a yarn cleaner for removing particles from a traveling yarn, a blade having an edge adjacent to the yarn, and a support for said blade permitting a movement of said edge having a component in the direction of travel of the yarn and a lesser component away from the yarn.

4. In a cleaner for removing particles from a traveling yarn, a blade having an edge adjacent to the yarn, and a support for said blade permitting movement of a point of said edge in a plane including the line of travel of the yarn and in a curve tangential to the yarn.

5. In a yarn cleaner for removing particles from a traveling yarn, a blade having an acute edge adjacent to the yarn and a front surface extending from said edge at an obtuse angle to the yarn, and a support for said element permitting reciprocal movement of said edge in directions approximately longitudinal of the yarn.

6. In a yarn cleaner for removing particles from a traveling yarn, a blade having an acute edge adjacent to the yarn and a front surface extending from said edge at an obtuse angle to the yarn, and a support for said blade permitting a reciprocatory movement of said edge having a component longitudinal of the yarn and a lesser component transverse to the yarn.
- 10 7. In a yarn cleaner for removing particles from a traveling yarn, a blade having an acute edge adjacent to the yarn and a front surface extending from said edge at an obtuse angle to the yarn, and a support for said blade permitting movement of a point of said edge in a plane containing the line of travel of the yarn and in a curve tangential to the yarn.
- 15 8. In a yarn cleaner for removing particles from a traveling yarn, a blade containing a notch partially encircling the yarn, and a support for said blade permitting a reciprocatory movement of said notch in directions approximately longitudinal of the 20 yarn.
- 25 9. In a yarn cleaner for removing particles from a traveling yarn, a blade containing a notch partially encircling the yarn, and a support for said blade permitting reciprocatory movement of said notch having a component longitudinal of the yarn and a lesser component transverse to the 30 yarn.
- 35 10. In a yarn cleaner for removing particles from a traveling yarn, a blade containing a notch partially encircling the yarn, and a support for said blade permitting movement of said notch in a plane containing the line of travel of the 40 yarn and in a curve tangential to the yarn.
- 45 11. In a yarn cleaner for removing particles from traveling yarn, a blade containing a notch partially encircling the yarn and having a front surface extending from said notch at an obtuse angle to the 45 yarn, and a support for said blade permitting a reciprocatory movement of said notch in directions approximately longitudinal of the 50 yarn.
- 55 12. In a yarn cleaner for removing particles from a traveling yarn a transverse blade having a point of its inner edge adjacent to the 55 yarn and mounted to permit a movement of said point having a component in the direction of travel of the yarn and a lesser component away from the 60 yarn, and resilient means tending normally to position the blade with said point in contact with the 65 yarn.
- 65 13. In a yarn cleaner for removing particles from a traveling yarn, a blade having an edge adjacent to the 70 yarn and mounted to permit a point of said edge to move in a plane containing the line of travel of the 75 yarn and in a curve tangential to the 80 yarn, and resilient means tending normally to position said blade with the edge of said 85 notch in contact with the 90 yarn.
- 90 14. In a yarn cleaner for removing particles from a traveling yarn, a blade having an acute edge adjacent to the 95 yarn and a front surface extending from said edge at an obtuse angle to the 100 yarn, said blade being mounted to permit reciprocatory movement of said edge in directions approximately longitudinal of the 105 yarn, and resilient means tending normally to position said blade with its acute edge in contact with the 110 yarn.
- 110 15. In a yarn cleaner for removing particles from a traveling yarn, a blade having an acute cleaning edge adjacent to the 115 yarn and a front surface extending from said edge at an obtuse angle to the 120 yarn, said blade being mounted to permit reciprocatory movement of said edge having a component longitudinal of the 125 yarn and a lesser component transverse to the 130 yarn, and resilient means tending normally to position said blade with its acute edge in contact with the 135 yarn.
16. In a yarn cleaner for removing particles from a traveling yarn, a blade having an acute edge adjacent to the 140 yarn and a front surface extending from said edge at an obtuse angle to the 145 yarn, said blade being mounted to permit movement of a point of 150 said edge in a plane containing the line of travel of the 155 yarn and in a curve tangential to the 160 yarn, and resilient means tending normally to position said 165 blade with its acute edge in contact with the 170 yarn.
17. In a yarn cleaner for removing particles from a traveling yarn, a blade containing a notch partially encircling the 175 yarn and mounted to permit reciprocatory movement of said notch in directions approximately longitudinal of the 180 yarn, and resilient means tending normally to position said 185 notch in contact with the 190 yarn.
19. In a yarn cleaner for removing particles from a traveling yarn, a blade containing a notch partially encircling the 195 yarn and mounted to permit movement of said notch in a plane containing the line of travel of the 200 yarn and in a curve tangential to the 205 yarn, and resilient means tending normally to position said blade with the edge of said 210 notch in contact with the 215 yarn.
20. In a yarn cleaner for removing particles from a traveling yarn, a blade con-

- taining a notch partially encircling the yarn and having a front surface extending from said notch at an obtuse angle to the yarn, said blade being mounted to permit reciprocatory movement of said notch in directions approximately longitudinal of the yarn, and resilient means tending normally to position said blade with the edge of said notch in contact with the yarn.
- 5 21. In a yarn cleaner for removing particles from a traveling yarn, a blade having an edge adjacent to the yarn, and a resilient support for said blade extending transversely to said edge of the blade and transversely 10 to the line of travel of the yarn.
- 15 22. In a yarn cleaner for removing particles from a traveling yarn, an element consisting of a single piece of sheet material and having an edge adjacent to the yarn and 20 a resilient portion extending transversely to said edge and transversely to the line of travel of the yarn to a fixed point of support.
- 25 23. In a yarn cleaner for removing particles from a traveling yarn, a blade having an acute edge adjacent to the yarn and a front surface extending from said edge at an obtuse angle to the yarn, and a resilient support inclined to said blade and extending 30 from the blade to a fixed point of support in a plane perpendicular to the yarn and intersecting the yarn at the point of the yarn adjacent to the acute edge of the blade.
- 35 24. In a yarn cleaner for removing particles from a traveling yarn, a cleaning element formed of a single piece of sheet material and consisting of a cleaning portion and a resilient portion inclined to the cleaning portion and extending to a fixed point 40 of support, the element being positioned so that a point of an edge of the cleaning portion lies adjacent to the yarn in a plane perpendicular to the line of travel of the yarn and containing said fixed point of support.
- 45 25. In a yarn cleaner for removing particles from a traveling yarn, a plurality of cleaning blades arranged on opposite sides of the yarn in staggered relation to each other and mounted for reciprocatory movement in directions approximately longitudinal of the yarn.
- 50 26. In a yarn cleaner for removing particles from a traveling yarn, a plurality of 55 cleaning blades arranged at opposite sides of the yarn in staggered relation to each other and resiliently mounted for free vibration in directions approximately longitudinal of the yarn.
- 60 27. In a yarn cleaner for removing particles from a traveling yarn, a plurality of notched cleaning blades spaced from each other longitudinally of the yarn, positioned so that the notch of each blade encircles a 65 different portion of the circumference of the yarn, and mounted for reciprocatory movement in directions approximately longitudinal of the yarn.
- 70 28. In a yarn cleaner for removing particles from a traveling yarn, a plurality of 75 notched cleaning blades spaced from each other longitudinally of the yarn and positioned so that the notch of each blade encircles a different portion of the circumference of the yarn, and resilient supports for said blades permitting them to vibrate freely in directions approximately longitudinal of the yarn.
- 75 29. In a yarn cleaner for removing particles from a traveling yarn, a pair of transverse blades located upon opposite sides of the 80 yarn and having spaced inner edges between which the yarn passes, and a support for each of said blades arranged to permit a movement of its inner edge having a component in the direction of travel of the yarn 85 and a component away from the edge of the other blade.
- 80 30. In a yarn cleaner for removing particles from a traveling yarn, a pair of transverse blades located upon opposite sides of the 90 yarn and having spaced inner edges between which the yarn passes, and a support for each of said blades arranged to permit a point of the inner edge of said blade to 95 move away from the inner edge of the other blade in a curve tangential to the yarn.
- 90 31. In a yarn cleaner for removing particles from a traveling yarn, a pair of transverse blades located on opposite sides of the 100 yarn and having spaced inner edges between which the yarn passes, and supports for said blades permitting them to turn outward from each other, the blades being oblique to the direction of such turning movement.
- 100 32. In a yarn cleaner for removing particles from a traveling yarn, a pair of transverse blades located upon opposite sides of the 105 yarn and having spaced inner edges between which the yarn passes, each of said blades being mounted to permit a movement of its inner edge having a component in the direction of travel of the yarn and a component away from the edge of the other blade, and resilient means tending normally 110 to position said blades with their inner edges in contact with the yarn.
- 110 33. In a yarn cleaner for removing particles from a traveling yarn, a pair of transverse blades located upon opposite sides of the 115 yarn, having spaced inner edges between which the yarn passes, and mounted to permit them to turn outward from each other, the blades being oblique to the direction of such turning movement, and resilient means tending normally to position the blades in line with each other.
- 120 34. In a yarn cleaner adapted to remove 125

- particles from a yarn traveling in a horizontal line, a pair of transverse blades having spaced inner edges between which the yarn passes and inclined from the vertical 5 so that their lower ends are to the rear of their upper ends, and horizontally yieldable supports for said blades permitting them to turn outwardly.
35. In a yarn cleaner for removing particles from a traveling yarn, a pair of transverse blades on opposite sides of the yarn having spaced inner edges between which the yarn passes, and a resilient support for each of said blades extending outward from 10 the yarn in a direction transverse to the inner edge of the blade.
36. A yarn cleaner for removing particles from a traveling yarn, comprising means for freeing particles adhering to the yarn, and 15 separate means providing an inclined deflecting surface transverse to the yarn and embracing the yarn behind said first means and adapted to direct the particles freed from the yarn by said first means away from 20 the line of travel of the yarn.
37. A yarn cleaner for removing particles from a traveling yarn, comprising a blade having a portion of its edge adjacent to the 25 yarn and resiliently held for free vibration 30 of said portion of said edge, so that the blade is set into vibration by the impingement on its edge of particles projecting from yarn and brushes particles from the yarn by its vibration, and means for directing particles loosened from the yarn by said cleaning element away from the line of travel of 35 the yarn.
38. In a yarn cleaner for removing particles from a traveling yarn, the combination 40 of a pair of cleaning blades yieldably mounted for free vibration and positioned to operate upon the traveling yarn on its entrance into the cleaner, and a plurality of 45 pairs of cleaning and deflecting blades yieldably mounted for free vibration and posi-
- tioned so that the yarn passes between said blades after passing said cleaning blades.
39. In a yarn cleaner for removing particles from a traveling yarn, the combination of a plurality of pairs of staggered resiliently mounted cleaning blades and a plurality of pairs of deflecting blades, a frame member to which one cleaning blade of each pair and one deflecting blade of each pair are secured, a second frame member to which the other cleaning blade of each pair and the other deflecting blade of each pair are secured, and means for adjustably varying the distance between said frame members to adapt the cleaner to yarns of different 50 diameters.
40. In a yarn cleaner, the combination with a plurality of yarn cleaning elements adapted to operate in series upon a traveling yarn and formed so as to be threaded by 55 transverse movement of the yarn in one direction, of a cover preventing access to the cleaning elements in the threading movement, said cover containing a slot extending across all the cleaning elements, and means 60 for guiding a yarn passed through said slot into operative relation with all the cleaning elements.
41. In a yarn cleaner for removing particles from a traveling yarn, a set of blades 65 at one side of the line of travel of the yarn having aligned semi-circular notches in their inner edges, a second set of blades at the other side of the line of travel of the yarn having in their inner edges aligned semi-circular notches substantially concentric 70 with the notches of the first set, and yieldable mountings for the blades of one set permitting their inner edges to move outward so that the yarn may be drawn into 75 said notches in threading the cleaner.
- In testimony whereof I have hereunto set my hand,

HENRY E. VAN NESS.
